UNITED STATES PATENT OFFICE.

HAROLD C. PYE, OF OAK PARK, ILLINOIS, ASSIGNOR TO AUTOMATIC ELECTRIC INC., OF CHICAGO, ILLINOIS, A CORPORATION OF DELAWARE.

ANTI-SIDE-TONE SUBSTATION CIRCUITS.

Application filed March 3, 1926. Serial No. 91,876.

This invention relates in general to telephone sub-station circuits, but more especially to sub-station circuits for common battery telephone systems; and the principal object 5 of the invention is to provide a new and improved common battery anti side-tone telephone circuit.

A further object of this invention is to provide a new and improved telephone sub-10 station circuit in which are combined the advantages of the well known booster-type circuit and the common battery anti side tone circuit.

A further object of this invention is to 15 provide an anti side-tone sub-station circuit equipped with a calling device to permit its use on an automatic telephone system.

A further object of this invention is to 20 provide an anti side-tone booster telephone circuit in which the amount of equipment required is reduced to a minimum without impairing the efficiency of the sub-station either during the sending or the reception of the telephone signals.

25 A still further object of this invention is to provide a direct current receiver comprising two windings which are so proportioned as to perform the functions of a receiver and an induction coil during the reception and transmission of signals by a telephone sub-station, and to also form the artificial line and balance necessary to secure the anti side-tone effect during the transmission of signals from the sub-station.

30 A still further object of this invention is to provide a sub-station circuit as above described adaptable for use in a cradle type telephone and using a three conductor cord to connect the hand telephone to the desk stand.

35 Further objects not specifically mentioned here, will be apparent from the detailed description and claims which follow.

The drawings comprising Figs. 1, to 5, inclusive, show the details of my invention. 40 Fig. 1 shows the invention adapted for use in a common battery manual telephone system, the transmitter and receiver being connected to the line equipment by means of the three cord conductors designated as C.

45 Fig. 2, shows the invention modified by the inclusion of the calling device comprising impulse springs 12 and shunt springs 13, the transmitter and receiver induction coil again being connected to the line equip-

ment by the cord conductors designated as C.

Fig. 3 shows the telephone circuit as shown in Fig. 2, with the modification in the ringer equipment, that modification comprising a three plate condenser in place of the ordinary two plate condenser shown elsewhere in the drawings. The inclusion of this three plate condenser permits the detaching of the ringer 6 from the line conductor 2 and attaching it to ground, thereby adapting the sub-station 60 to use in a ground ringing system.

Fig. 4 as a schematic diagram of the sub-station circuits during the transmission of signals from the sub-station.

Fig. 5 is a schematic drawing of the sub-70 station circuit during the reception of the signals by the sub-station.

Numerous anti side-tone sub-station telephone circuits have been devised prior to my invention, the various circuits obtaining the 75 anti side-tone feature, by means of an electrical balance which reduces the two ends of the receiver to the same potential during the transmission of signals from the sub-station. That is, in the sub-station circuit, the ordinary permanent magnet or the direct current receiver is employed in connection with an induction coil having three or more windings, the added windings together with suitable condensers and resistance coils forming a so called artificial line whose electrical constants approximate those of the line on which the sub-station is being used. The receiver employed in such a circuit is so connected that during transmission 80 of signals by the transmitter of the sub-station, the currents generated therein, will divide themselves in the electrical net work in a manner similar to the current division in the well known Wheatstone bridge. The 85 receiver which occupies the position in the bridge circuit corresponding to the galvanometer, is unresponsive for the reason that its two terminals are reduced to the same potential.

90 This system of balancing the electrical circuit of a telephone substation so that the receiver terminals are brought to the same potential during transmission of signals from the substation, will produce absolute anti 95 side-tone effect only on the line whose circuit characteristics are identical with the characteristics of the artificial line built in the substation, and then only on one particular frequency. However, absolute anti 100 side-tone effect can be obtained on any line 105 whose circuit characteristics are identical with the characteristics of the artificial line built in the substation.

110

side-tone effect is not necessary, provided the side-tone is reduced to the point where it is unnoticeable to the user of the telephone. Anti side-tone sub-station circuits built in accordance with the foregoing principle, require an appreciable amount of extra equipment over and above the usual instrumentalities found in a common battery booster telephone, this extra equipment adding materially to the cost of production of the substation.

In order to reduce the cost of manufacture of the substation as much as possible, I employ a direct current receiver, comprising two windings, which are so proportioned that they may serve as the windings of an induction coil, and so connected as to form the well known booster sub-station circuit. With an arrangement of this kind, I make no attempt to reduce the two terminals of the receiver to the same potential during the transmission of signals from the substation, rather I so proportion the windings of the receiver induction coil so that during transmission, the voltage generated in the transmitter, drives current through the receiver windings in opposite directions, those windings being proportioned so that the current turn effect of these two currents is equal and opposite, and consequently no magnetism is set up in the core of the receiver and the substation is consequently anti side-tone. The substation built in the foregoing manner is very cheap to manufacture, for the reason that it eliminates the costly permanent magnet receiver, the multiwinding induction coil and reduces the number of conductors required between the transmitter receiver unit and the line equipment to a minimum.

Referring now to Fig. 1 in more detail, across the incoming line conductors 1 and 2, I have bridged the signalling equipment comprising the condenser 5 and the ringer 6. This bridge is permanently closed. I have provided the ordinary two circuit hook-switch which comprises springs 10 and 11, which are opened when the substation is retired from use, to open the direct current bridge across the line conductors 1 and 2. The transmitter 3 employed in this circuit may be any well known common battery transmitter, and the receiver comprising the windings 7 and 8 and the resistance 9 is of the direct current type, employing an E shape magnetic iron core, with the coils mounted on the middle portion.

In Fig. 2, I have modified the substation circuit of Fig. 1, by the inclusion of the calling device comprising springs 12 and 13, and further modified it by moving the resistance 9 from the receiver element, and attaching it to the condenser 5 in the same relative position in the circuit during the transmission and reception of telephone

signals, but in such a position that it is not shorted out by the shunt springs 13 during the impulsing period but rather is in the spark quenching circuit provided for the impulse springs 12, as will be pointed out presently. In the receiver 4, shown in Fig. 1, the resistance 9 which is in series with the winding 8 of the receiver, may be in the form of a separate resistance coil attached to the winding 8 within the receiver proper; or it may take the form of distributed resistance in the winding 8, in which case the winding is made the same number of turns of a smaller size wire so chosen as to have a resistance comparable with the combined value of the resistance of the coils 8 and 9 if a separate resistance element is used.

Fig. 4, shows the details of the talking circuit of any of the above figures, with arrows indicating the instantaneous direction of the alternating currents during the time that the substation is transmitting, that is, when the subscriber is talking into the transmitter 3. The varying transmitter resistance together with the current flowing in the line circuit, produces an effect equivalent to setting up in the transmitter a variable electromotive force which causes an alternating current to flow. This alternating current is superimposed upon the direct current flowing in the line circuit. The alternating current set up by the transmitter flows over a main circuit including the winding 8 of the receiver, the resistance 9, the condenser 5, and the connections between those elements and the transmitter. The windings 7 and 8 of the receiver form an auto transformer, with the winding 8 as the primary, the winding 7 as the secondary. The alternating current flowing through the winding 8 induces, in the winding 7, voltage which adds to the voltage across the terminals of the transmitter, so that the voltage impressed upon the line terminals 1 and 2 is greater than that at the terminals of the transmitter, thereby producing the well known booster substation circuit.

The current-turn ratios of the windings 7 and 8 are so chosen that when combined with the resistance 9 and the condenser 5, the current-turn strength of the winding 8 substantially neutralizes the current-turn strength of the winding 7, thereby substantially preventing flux variations in the core of the receiver 4. The core is magnetized by the direct current flowing through the winding 7, however, this magnetization is practically constant and the diaphragm will not be moved. The circuit is therefore anti side tone.

Referring now to Figure 5, which shows the sub-station with arrows indicating the current flow during the reception period, that is, when the source of potential is across the line conductors 1 and 2, the current

coming in over the conductor 1, tends to divide in two paths, the one including the transmitter 3 and the winding 7, of the receiver to the line conductor 2, and the other including the condenser 5, the resistance 9, and the windings 8 and 7, of the receiver in series to the line conductor 2. The current flowing through the transmitter and winding 7 of the receiver, sets up in the core 5 of the receiver magnetism which induces in the winding 8, a back E. M. F. which opposes the flow of alternating current in that winding, so that the portion of incoming current flowing over the last named parallel 10 branch is extremely small. The flux set up by the current flowing in the winding 7, acts upon the diaphragm of the receiver, to reproduce the incoming sound signal. Since the voltage induced in the winding 8, virtually 15 prevents the flow of any alternating current through that winding, all of the energy received from the line conductors 1 and 2, except for a small part expended in the transmitter 3, is available to actuate the 20 diaphragm of the receiver. By properly proportioning the winding 7, with respect to the transmitter 3, and the winding 8 the resistance 9, and condenser 5, I am able to construct a receiver which will receive the maximum 25 possible amount of energy from the line circuit.

This should be noted in both Figures 4 and 5, that the receiver windings 7, 8, and the resistance 9, are shunted by the ringer 6, which constitute a complete circuit for both direct and alternating currents. However, the ringer is so constructed as to have a high resistance, and an even higher impedance, and therefore, the direct and alternating current flowing through this ringer is so small as to be negligible in amount and effect, during the transmission and reception of signals by the substation.

Referring now, particularly to Fig. 2, it will be noted, that I have removed resistance element 9 from the receiver 4, and connected it adjacent to the condenser 5. When the calling device comprising springs 12 and 13, is operated, spring 13 operates first to close 40 a shunt circuit, which shunts out the transmitter and receiver as long as the calling device remains in an off-normal position. Subsequent to the operation of springs 13, the impulse springs 12 are alternately opened 50 and closed, to intermittently open the line circuit to transmit impulses to the automatic switches at the central station. When the springs 12 open the line circuit, they open the circuit of a high inductance relay 60 in the exchange, with a resultant inductive kick which impresses a rather high voltage on the line conductors 1 and 2, unless protective means are provided this high voltage will cause an arcing of the contacts 12, and 65 will damage those contacts to the point of

uselessness. As is the custom in telephone sub-station circuits of this kind, I have provided a condenser 5 which is in a circuit so as to be bridged across the contacts 12 when those contacts are open, the condenser absorbing a charge responsive to the high voltage on the line terminal. When the springs 12 again close their contacts, the condenser is discharged by being short circuited by the springs 12 and if no retarding means are 70 provided, considerable instantaneous current would flow from the condenser with detrimental effect upon the contacts 12. By removing the resistance 9 from the receiver, and attaching it as shown in Figure 2, I 75 provide a retarding means which is not short circuited, since the circuit for the condenser 5, closed by the contact springs 12, includes the resistance 9 and the ringer in parallel, shunt spring combination 13, to the one side 80 of the spring 12, and hook switch 10 to the other side of the condenser. This resistance is of such a value that it retards the discharge of the condenser 5 sufficiently to protect the contacts 12 of the calling device 85 from serious damage.

A further advantage is gained by placing the resistance 9 on the condenser as shown in Fig. 2. During impulsive the operating of shunt springs 13 place the resistance 9 90 directly across the terminals of the ringer 6, thereby shunting the ringer to guard against its tapping when the impulse springs 12 open the line circuit and the condenser 5 is being charged, as explained above. This 100 arrangement makes possible the removal of the biasing spring with which ringers such as 6 are usually equipped.

In Fig. 3, I have shown the circuit as Fig. 2, modified by the inclusion of a 3 plate 105 condenser, designated as 5 and 5', the 5' portion of the condenser being the ringing condenser and being so arranged as to permit the transfer of the connection of the ringer 6 from the line conductor 2 to a ground 110 connection to permit grounded ringing, as is the custom in some telephone systems. Three plate condensers, such as I have shown here are formed by rolling three conducting plates together, with a suitable dielectric 115 interposed between the plates, and with a suitable terminal attached to each plate. Such a condenser has the same capacitance between any two of its terminals.

When a three plate condenser is used in 120 connection with the circuits above referred to, the shunt around the ringer is interrupted by the condenser and ground connection of the ringer. When the impulse springs 12 interrupt the line circuit, the condenser plate connected to the conductor 1 will be charged to one potential, and the plate connected to the conductor 2 through the resistance 9 will be charged to an equal and opposite potential. The third condenser plate being in 125 130

terposed between the other two plates will be neutralized and will not receive any charge, consequently the ringer, which is connected to this third plate, will receive 5 no current and will not tap.

If desired the three plate condenser may be replaced by two condensers, which may be of different capacity if ringing conditions require. In this case, the ringer must be 10 equipped with the usual biasing spring to prevent its tapping during impulsing.

There are many modifications in the details of the above circuits which may be made by one skilled in the art without departing from the scope of the invention. For example it may be advantageous to install a condenser such as 5 in the hand telephone, in the same relative circuit position as shown above. This will produce a hand 20 telephone requiring only a two conductor cord, an instrument usable without a bell box for extension phone installations. The hand telephone so constructed will be fully anti side-tone incorporating all the principals 25 hereinbefore set forth.

Having thus described my invention what I consider new and desire to have protected by Letters Patent is pointed out in the appended claims.

30 What is claimed is:

1. In an anti side-tone substation, a transmitter, a receiver having two windings, a resistance, a condenser, a ringer, a line circuit, means for connecting said instrumentalities across said line circuit to form an anti side-tone booster substation, a calling device having impulse springs in series with said line circuit and shunt springs for short circuiting said transmitter and receiver 35 while said dial is being operated, said shunt springs also bridging said impulse springs with said condenser and resistance to eliminate sparking and connecting said resistance in multiple with said ringer to prevent its tapping during impulsing.

45 2. In a substation set, a line circuit, a

transmitter, a ringer and condenser, a resistance, a hook switch having a plurality of normally open contact sets, a receiver having a pair of differentially wound windings, one 50 of said windings in series with the line circuit and the other in a shunt path around the transmitter, a calling device in said set having impulse springs operated and shunt springs closed during the operation thereof, 55 a circuit closed by said shunt springs short circuiting both windings of said receiver and connecting said resistance and a hook switch spring in a series multiple combination with said ringer, and another circuit closed by 60 said shunt springs shunting one winding of said receiver around said transmitter and shunting a second hook switch contact set, said condenser and resistance around said impulse springs, said condenser and hook switch contact sets in their normal position preventing said shunt spring circuits from 65 short circuiting said line circuit.

3. In a telephone substation set, a receiver having two windings, a line circuit, a transmitter, a calling device having impulse springs and shunt springs, a condenser and ringer, a resistance, said condenser and ringer forming a permanent bridge across 70 said line circuit, said impulse springs, transmitter and one winding of said receiver forming a second bridge across said line and said second winding and resistances forming 75 a shunt path between the mid points of said first and second bridges to form an anti side tone booster substation, and means including 80 said shunt springs operated during the operation of said calling device to shunt out said transmitter and receiver and to connect said resistance in multiple with said 85 ringer to prevent its tapping and to lower the impedance of said first bridge to prevent 90 sparking at said impulse springs.

In witness whereof, I hereunto subscribe my name this 26th day of February, A. D., 90 1926.

HAROLD C. PYE.
